UNITED STATES PATENT OFFICE.

LOUIS S. HUGHES, OF CHICAGO, ILLINOIS.

APPARATUS FOR PRODUCING SUBLIMED LEAD.

1,070,688.

Specification of Letters Patent. Patented Aug. 19, 1913.

Application filed January 13, 1913. Serial No. 741,659.

To all whom it may concern:

Be it known that I, LOUIS S. HUGHES, a citizen of the United States, residing at Chicago, in the county of Cook and State 5 of Illinois, have invented certain new and useful Improvements in Apparatus for Producing Sublimed Lead, of which the following is a specification, reference being had therein to the accompanying drawing.

10 My invention relates to a new and improved apparatus for producing sublimed lead, and consists in the matters hereinafter described and then pointed out in the appended claims.

15 The manufacture of sublimed lead is accomplished commercially by feeding lead bearing materials (largely native lead sulfid or galena) into an open coke fire in short blast-furnaces (the so-called "low cupola" 20 furnaces), the fire being maintained by air blast through tuyers placed near the bottom of the furnaces and continuous operation being secured by feeding with the coke and lead and sulfur bearing charge proper amounts 25 of lime and iron to form a fluid slag with the silicious coke ash and gangue of the ore. Slag pots are provided for the removal of this slag. The white fume of oxidized lead compounds rises from the fire as a dense 30 white smoke and is drawn from the furnace into a horizontal brick flue where the last traces of carbon (soot) and lead sulfid are burned, and the gases and fume pass thence into a series of settling and cooling chambers 35 within which the last traces of fire dirts and iron oxid settle out, and after being thus purified by gravitational subsidence of the impurities and cooled by radiation until the fume and gases can be passed through cloth

40 filters they enter a screen system of the ordinary bag room type where the air and furnace gases pass through the filter cloths and the fume is retained therein. Draft for the furnaces and for drawing the gases and fume through the flue and cooling system 45 into the bag room is secured by placing a large suction fan between the cooling system and the bag room. This draws the gases and fume from the furnaces, through the system 50 and forces them into the filter system, the fan, of course, acting as a suction fan on one side and a pressure fan on the other.

The apparatus heretofore employed for the manufacture of sublimed lead comprises two or more "low cupola" furnaces placed side by side in tandem and opening into a common combustion chamber which delivers into a brick flue placed at one end of the row of furnaces. Feed doors are placed along one side of the wall of the combustion chamber at a level with the tops of the furnaces. At the end of the flue is a series of settling chambers and cooling pipes with a suction flue to supply draft to the furnace doors and to convey the fumiform pigment to a screen system wherein it is collected. While the fire in the furnaces is maintained by blast tuyers placed near the bottom of the furnaces, very little, if any, of the air supplied by these tuyers is available for oxidation of the ore as it is deprived of its oxygen while passing over the incandescent coke within the furnace and practically all the oxidation of the ore is accomplished by air drawn into the feed doors over the tops of the furnaces. As the suction draws the air to one side as soon as it enters the feed doors and its expansion by heating upon entering the door tends to cause it to rise toward the top of the combustion chamber, whence it is drawn into the flue, without again coming in contact with the furnace top, the air is only in effective contact with the charge near the front edge of the furnace tops and the rear of the furnace remains under a blanket of dead or reducing gas arising from the furnaces below. So extreme is this reducing condition at the back of the furnaces that smoke allowed to escape through a hole in the back of the combustion chamber is black from unburned carbon and lead sulfid.

As the oxidation by the furnaces is incomplete a very considerable proportion of the lead in the charge is reduced to metal and is recovered with the slag, but this is an undesired and unprofitable by-product. Efforts have been made to secure more complete oxidation by the furnaces in order to reduce this proportion of pig lead. For example, the use of single furnaces has been attempted but without practical success as a single furnace cannot be employed commercially for the reason that either through oc-

casional bad practice or irregular charging or obstruction in operation of the furnace the fire becomes smoky instead of bright and thus fails to maintain the flue at a temperature sufficient to consume all the discoloring smoke entering it. The result is the entry of discoloring carbon or vaporized sulfid into the collecting chamber with the consequent discoloration of all the product then in the collecting chamber. As the value of the product is dependent upon its whiteness and even a trace of discoloration is sufficient to render it valueless commercially, it is apparent that even the lapse of a few minutes in proper operation will ruin a whole day's product. Another arrangement consisted in placing furnaces at the ends of converging flues but this failed because it is practically impossible to maintain an equal draft through the branches of a converging flue. If one furnace is (as must often be the case) hotter than the other the expansion of air within it causes the draft to seek entry through the cooler furnace and flue to such an extent that the hot furnace will emit smoke at the doors. This causes not only a loss of the product but it also causes poisoning among the operatives as all lead vapors are highly toxic.

As the yield of a furnace in sublimate depends entirely upon the amount of oxidation effected it is manifest that this yield will be very greatly increased if the entire top of the furnace be maintained under oxidizing instead of indifferent or reducing conditions. By my present invention I maintain the flue at proper working heat and secure complete oxidizing conditions over the entire top of the furnace, and I accomplish these results by placing two or more furnaces "abreast" instead of "tandem" and by placing a draft port or ports at or near the top of the furnaces opposite the feed doors and enlarging the flue at its near end into a chamber, whereby an equal draft is secured over the entire top of each furnace, thus rendering effective for oxidation the entire area of the furnace top.

In the accompanying drawings which illustrate a practical embodiment of my invention, Figure 1 is a longitudinal horizontal sectional view showing the arrangement of the furnaces, chamber and flue, and Fig. 2 is a longitudinal vertical sectional view of the same parts.

In the drawings the reference letter A designates a plurality of furnaces having feed doors B and arranged in the inclosing housing or casing C abreast of each other with respect to the flue, and the casing provides a chamber D formed by an enlargement of the flue E and communicating with the area above the tops of the furnaces by a draft port F formed by the masonry of the casing with a flat arched top. The

chamber D acts as an equalizing chamber on the draft and is of sufficient size to diffuse the suction influence of the flue and cause an equal draft at the furnace ports. In practice I have found that uniformity of draft is secured by using a chamber six feet high, twelve feet wide and twelve feet long provided with port of total cross-sectional area not exceeding sixteen square feet arranged across its front end with a flue of cross-sectional area of approximately sixteen square feet, though of course these relative dimensions may be varied. The chamber at its rear merges into the flue which should be at least equal in cross-sectional area to the total area of the interior draft ports F of the furnace. The chamber is preferably circular or elliptical in its ground plan or horizontal cross-section as such formation eliminates the settling which otherwise occurs in corners and also furnishes a construction less liable to crack on heating.

As many furnaces as desired may be arranged side by side, and in practice I prefer to make the draft port common to all furnaces employed as the less divisions there are in it the less likely is it to fill up.

By the organization disclosed the air is effective with the charge over the entire area of the furnace tops and complete oxidizing conditions are obtained thereby making a larger yield of pigment and less pig lead. Also for this reason the quality of the pigment is better and more uniform than by former apparatus. The enlargement of the flue constituting the chamber into which the draft ports lead diffuses or equalizes the suction influence of the flue over the several furnaces so that an equal draft is effected at all the furnace ports. The improved drafting of the furnaces maintains the flue at proper working heat so that the life of the apparatus is prolonged as there is no liability of its filling up by deposits which usually begin at the start of firing operations and accumulate during operation, and as the improved drafting practically aerates the entire furnace chamber there are no wall accretions to cause shut-downs and impair the usefulness or interrupt the use of the apparatus.

I claim:

1. In a device for producing sublimed lead, a plurality of furnaces arranged abreast and having air intakes near their tops, a flue, and a chamber between the flue and furnaces communicating with the latter by draft port near their tops, said port having approximately the area of the cross-sectional area of the flue, and the chamber being larger in diameter than the flue.

2. In a device for producing sublimed lead, a plurality of furnaces arranged abreast and having air and feed doors near their tops, a flue, and a chamber between the flue

and furnaces and communicating with the latter by draft port opposite the feed doors, said port having approximately the area of the cross-sectional area of the flue, and the 5 chamber being elliptical in ground plan and having its sides merging into the sides of the flue.

In testimony whereof I affix my signature in presence of two witnesses.

LOUIS S. HUGHES.
